UNITED STATES PATENT OFFICE

2,277,121

ELECTRIC DISCHARGE DEVICE

Edmund Löpp, Berlin, Germany, assignor to C. Lorenz Aktiengesellschaft, Berlin-Tempelhof, Germany, a company

Application February 4, 1941, Serial No. 377,311
In Germany January 20, 1940

4 Claims. (Cl. 250—27.5)

This invention relates to the means by which an electron tube and its socket are interconnected, and is more particularly concerned with short-wave tubes of the kind having their bulb made of pressed glass.

One feature of the invention is that the bottom of such glass bulb is used as a stop for the socket, the accuracy in the manufacture of pressed glass bulbs being such that the tolerances concerned are not greater than ± 0.1 millimeter, as has been proved by numerous tests.

In the drawing, Fig. 1 is a partially diagrammatic sectional view illustrating one embodiment of the invention, Fig. 2 shows a section on line 2—2, Fig. 1, while Fig. 3 is a sectional view representing a slight modification of the socket shown in Figs. 1 and 2.

1 denotes the socket while 2 indicates the electron tube whose bulb is made of pressed glass. The bottom A of the bulb has a re-entrant flat part in which the lead-in conductors 3 are mounted. These conductors are to engage with contact springs which form part of the socket. For simplicity these springs are not illustrated.

Bottom A is shaped to grip over a central annular projection or upturned edge B of the socket 1 and thus serves as a stop intended to come against the edge B as counter-stop.

Bottom A is formed with lugs C for notches D provided in the edge B. The lugs enter the notches if socket 1 and tube 2 are in the proper angular position with respect to each other, that

is, the position necessary for the conductors 3 engaging with the proper contact springs of the socket.

The parts A, B thus constitute a sort of coarse guide, while C, D constitute the fine guide.

The socket shown in Fig. 3 has a circumferential projection or upturned edge E that serves as an additional guide for the electron tube.

What is claimed is:

- 10 1. An electric discharge device comprising an electron tube and a socket therefor, this tube having a bottom arranged to act as a stop adapted to come against a stop forming part of the socket, the stop of the socket being a central annular projection thereof while the said bottom is shaped to grip over this projection.
- 20 2. A discharge device according to claim 1, wherein the stop of the socket is a central annular projection thereof and which comprises guide means to insure a determinate angular position of the electron tube with respect to the socket.
- 25 3. A discharge device according to claim 1, wherein the stop of the socket is a central annular projection thereof and which comprises notches and lugs of such projection and said bottom to insure a determinate angular position of electron tube and socket.
- 30 4. A discharge device according to claim 1, wherein the socket has a circumferential projection as an additional guide for the electron tube.

EDMUND LÖPP.
